DESIGN FOR A DOLL

Alma Mae De Journette, Chattanooga, Tenn.

Application December 31, 1936, Serial No. 66,828

Term of patent 7 years

To all whom it may concern:

Be it known that I, Alma Mae De Journette, a citizen of the United States, residing at Chattanooga, in the county of Hamilton and State of Tennessee, have invented a new, original, and ornamental Design for a Doll, of which the following is a specification, reference being had to the accompanying drawing, forming part thereof.

Figure 1 is a front view of a doll, showing my new design;

Figure 2 is a fragmentary rear view thereof; and

Fig. 3 is a vertical sectional view taken on the line 3—3 of Fig. 1.

The doll comprises a flat figure, as shown, having artificial hair, both at the front and rear of the head, and secured thereto primarily by passing through an opening near the top thereof, said hair forming bangs projecting from the front of the head, and at the back falling in a wavy mass and standing out from the back of the head and extending beyond each side thereof and down over the neck.

I claim:

The ornamental design for a doll, as shown and described.

ALMA MAE DE JOURNETTE.
